UNITED STATES PATENT OFFICE.

FRANCIS F. PRENTISS, OF CLEVELAND, OHIO.

DESIGN FOR A COMBINED TAP AND DRILL.

SPECIFICATION forming part of Design No. 30,485, dated April 4, 1899.

Application filed March 8, 1899. Serial No. 708,284. Term of patent 14 years.

To all whom it may concern:

Be it known that I, FRANCIS F. PRENTISS, a citizen of the United States, residing at Cleveland, in the county of Cuyahoga and State of Ohio, have invented and produced a new and original Design for a Combined Tap and Drill, of which the following is a specification, reference being had to the accompanying drawings, forming part thereof.

10 In the accompanying drawings, Figure 1 is a plain elevation of my new design in a combined tap and drill. Fig. 2 also is a plain elevation of the design like unto Fig. 1, but substantially at right angles thereto and disclosing a notable peculiarity in the head seen from this point of view alone in its fulness. Fig. 3 is a cross-section, looking down, on line 3 3, Fig. 1.

As seen in the several views, the design is 20 distinguished from all others known to me and original and novel in conception in the appearance particularly of the head A, with its spiral formations extending the full length of the head and the associated features entering 25 into differentiate the lower portion of the head from all resemblance to or likeness of other articles in this line.

The upper portion of the head is marked by a series of spiral ribs 2 and flutes 3, alternately 30 running right or left and uniform with each other in their series, and the ribs are ornamented by a series of transverse elevations

or elevations and depressions alternately substantially V shape in cross-section.

The lower portion of the head has its extremity 5 defined by two converging downwardly-inclined lines 6, substantially opposite and in line, as seen in Fig. 3, and these two lines are lost in Fig. 2, where they intersect with other two lines 7, inclined toward each other as they extend upward and inward, and form the boundary, in part, of deep side depressions in the head. The upper portion of these opposite depressions are outlined by curved or segmental lines 8.

Intermediate of the several lines 5, 6, 7, and 8, as viewed more particularly in Fig. 1, are deep and peculiarly-shaped cavities 9, which, as seen in Fig. 3, have only a comparatively light portion of stock between them, which, 50 however, deepens toward the top on a curved line indicated by the curvature of the cavity 9. These cavities have, besides, a spiral declension, placing them in harmony with the associated flutes and ribs above.

What I claim is—

The design for a combined tap and drill, substantially as herein shown and described.

Witness my hand to the foregoing specification this 11th day of February, 1899.

FRANCIS F. PRENTISS.
